UNITED STATES PATENT OFFICE.

HERMANN FREYTAG, OF STUTTGART, GERMANY.

POKER OR BRANDING-TOOL FOR USE IN PYROGRAPHY.

SPECIFICATION forming part of Letters Patent No. 724,002, dated March 31, 1903.

Application filed October 5, 1900. Serial No. 32,182. (No model.)

To all whom it may concern:

Be it known that I, HERMANN FREYTAG, merchant, a subject of the King of Würtemberg, residing at Stuttgart, Kingdom of Würtemberg, German Empire, have invented new and useful Improvements in Pokers or Branding-Tools for Use in Pyrography, of which the following is a specification.

The present invention relates to an improved poker or branding-tool for use in pyrography which is constructed in such a manner that the smoke, benzin-vapors, and fumes largely developed during the operation are blown forward or away from the operator automatically and without cooling down the working point.

I will now proceed to describe my invention more fully, reference being had to the accompanying drawings, in which—

20 Figure 1 illustrates a view of an apparatus complete as used in pyrography. Fig. 2 shows the receiver of the poker or branding-tool on an enlarged scale. Fig. 3 illustrates a section on line A B, and Fig. 4 illustrates 25 a central vertical section through Fig. 2.

The end of the tube *a* is coupled to the flexible tube *c* of the benzin apparatus *b* in the well-known manner. Into the front end of the tube *a* the branding-tool receiver *d* is 30 screwed, the poker or branding-tool *e* being inserted into the front end of this receiver *d*. At the right and left of the central bore *h* of the receiver *d* openings *i* *k* are provided, which terminate in exhaust-holes *f* *g* externally of 35 the operating-tool *e*. The operating-tool *e* is

hollow and provided with exhaust-openings *l* *m* at its rear end. The tool *e* has one side shaped and sharpened like a knife, the other side being rounded.

When employing an operating-tool of the hereinbefore-described kind in the art of pyrography, the air for blowing away the benzin-vapors is heated with said benzin-vapors inside the glowing-tool and escapes through the openings *l* *m* in the tool and 45 through the openings *f* *g* at the front of the receiver. In this manner the benzin-vapors are carried away automatically from the operator, on the one hand, and, on the other hand, the tool is prevented from cooling down by 50 virtue of blow-off air-currents.

What I claim as new, and desire to secure by Letters Patent, is—

An improved poker or operating-tool for use in pyrography with a hollow operating-point, knife-like sharpened at one side and rounded at the other side, exhaust-openings at the rear end of the hollow operating-point and exhaust-openings at the front end of the tool-carrier communicating with the exhaust- 60 openings at the rear end of the operating-point, substantially as described and shown and for the purposes set forth.

In testimony whereof I have hereunto set my hand in presence of two subscribing witnesses.

HERMANN FREYTAG.
